US00D820980S

(12) **United States Design Patent** (10) **Patent No.:** **US D820,980 S**
(45) **Date of Patent:** **** Jun. 19, 2018**

(54) **ENDOSCOPE CONNECTOR**

(71) Applicant: **ERBE-USA, Inc.**, Marietta, GA (US)

(72) Inventor: **Daniel G. Maurice**, Monument Beach, MA (US)

(73) Assignee: **ERBE-USA, Inc.**, Marietta, GA (US)

(**) Term: **15 Years**

(21) Appl. No.: **29/605,344**

(22) Filed: **May 25, 2017**

Related U.S. Application Data

(62) Division of application No. 29/548,906, filed on Dec. 17, 2015, now Pat. No. Des. 791,310, which is a division of application No. 29/485,453, filed on Mar. 19, 2014, now Pat. No. Des. 750,236.

(57) **CLAIM**

The ornamental design for an endoscope connector, as shown and described.

DESCRIPTION

FIG. 1 is a perspective view of an endoscope connector;

FIG. 2 is a second perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines shown in FIGS. 1-7 illustrate portions of the endoscope connector that form no part of the claimed design. The dash dot lines illustrate the boundary of the claimed design and form no part of the claimed design.

1 Claim, 5 Drawing Sheets
